UNITED STATES PATENT OFFICE

EMMETT W. FINCH, OF CHICAGO, ILLINOIS

WASHING MACHINE

Application filed February 5, 1930. Serial No. 426,152.

This invention relates to washing machines and to means for operating the same, an object being to provide a power mechanism in which power derived from the rocking motion of a chair is utilized, so that the machine may be operated in comfort and with a minimum of effort.

Another object of the invention is the provision of a frame of novel construction which supports the washing cylinder or container and supports and guides the chair, together with means for operatively connecting the chair and cylinder, whereby the latter may be operated.

Another object of the invention is the provision of a cylinder or container of novel construction, wherein the contents thereof will be moved both circumferentially and longitudinally, so that the said contents will be thoroughly agitated and a thorough cleansing of the articles ensue.

With the above and other objects in view, the invention further includes the following novel features and details of construction, to be hereinafter more fully described, illustrated in the accompanying drawings and pointed out in the appended claims.

Figure 1 is a side elevation illustrating the invention.

Figure 2 is a top plan view.

Figure 3 is a sectional view taken longitudinally of the tub.

Figure 4 is a perspective view of the washing cylinder or container.

Figure 5 is a section on the line 5-5 of Figure 1.

Figure 6 is a similar view on the line 6-6 of Figure 1.

Referring to the drawings in detail, where-in like characters of reference denote corresponding parts, the reference character 10 indicates the frame of the machine which may be constructed of both angle iron and strap iron so as to provide a relatively light rigid frame. This frame rotatably supports a cylinder or container 11 whose trunnions 12 are mounted in bearing arms 13 secured to the frame. One of these trunnions carries a gear 14 which is engaged by a pinion 15, and the latter is mounted upon a shaft 16, one

end of which has a bearing in one of the bearing arms 13 while the other end extends through a bearing 17 carried by the frame and has secured thereto a fly wheel 18.

The container 11 is substantially cylindrical and is provided with oppositely located flat sides 19. These sides are disposed at an inclination with respect to the axial center of the cylinder, and when the said cylinder is revolved, the articles therein will be moved circumferentially and longitudinally. This circumferential movement is due to the flat portions 19, while the longitudinal movement is due to the inclination of these flat portions with respect to the axis of rotation.

The cylinder or container 11 operates in a tub 20 which is supported by the frame 10 and which is adapted to contain water for washing the articles within the container. The walls of the cylinder or container are perforated as indicated at 21 so that the water may pass through the cylinder and through the articles therein. The cylinder or container is provided with an opening for the insertion and removal of the articles and this opening is closed by a door 22. The door is hinged as shown at 23 and is provided with a suitable latch operated by a knob 24.

The frame 10 includes an extension 25. This extension comprises spaced parallel angle rails 26 which are connected by bars 27, the frame extension being rigidly connected with the frame proper by means of crossed bars 28.

The rails 26 provide tracks or guides for the rockers 29 of a chair 30, and these rockers may also be formed of angle iron so as to engage and ride upon the rails 26, as clearly shown in Figures 1 and 6 of the drawings.

The chair is connected to one of the cross bars 27 of the frame 25 by means of a spring 31, while a spring 32 connects the front of the chair with the main portion of the frame, so that the action of these springs will be to assist in the rocking motion after such motion is begun.

Pivotedly connected with the chair 30 is a yoke 32. This yoke extends across the back of the chair 30 and is removably engaged within open bearing members 33. An arm 34

which extends through the yoke is eccentrically pivoted to the fly wheel 18 as shown at 35. Thus rocking movement of the chair 30 will, through the yoke and arm, rotate the fly wheel 18 and operate the cylinder 11.

8 The invention is susceptible of various changes in its form, proportions and minor details of construction and the right is herein reserved to make such changes as properly fall within the scope of the appended claims.

10 Having described the invention what is claimed is:—

1. In a washing machine, a frame, a cylinder mounted for operation therein, a frame extension including spaced parallel angle rails, means rigidly connecting the frame extension and frame, a rocking device having parts movably engaging the rails, springs connecting the device and frame extension 15 and the device and frame, and means operatively connecting the device and cylinder to operate the latter when the device is rocked.

2. In a washing machine, a frame, a cylinder mounted for operation therein, a frame extension including spaced parallel angle rails, means rigidly connecting the frame extension and frame, a rocking device having parts movably engaging the rails, springs connecting the device and frame extension 20 and the device and frame, a yoke pivotally 25 connected with the device, an arm extending from the yoke, and an eccentric connection between the arm and cylinder to operate the latter when the device is rocked.

30 35 In testimony whereof I affix my signature.
EMMETT W. FINCH.
